(57) **CLAIM**

The ornamental design for a security camera housing, as
shown and described.

DESCRIPTION

FIG. 1 is a front, bottom, and left side perspective view of a
security camera housing according to our design.

FIG. 2 is a front elevation view thereof.

FIG. 3 is a left side elevation view thereof.

FIG. 4 is a right side elevation view thereof.

FIG. 5 is a rear elevation view thereof.

FIG. 6 is a bottom plan view thereof; and,

FIG. 7 is a top plan view thereof.

In FIG. 5, the dotted/dashed lines immediately adjacent solid
lines represent unclaimed boundaries of the claimed design
and, as such, the configuration of the unshaded surfaces
defined by those dotted/dashed lines form no part of the
claimed design.

Portions of the security camera housing not shown in the
Figures and not otherwise described in this specification do
not form part of the claimed design.
